UNITED STATES PATENT OFFICE.

CARLETON ELLIS, OF MONTCLAIR, NEW JERSEY, ASSIGNOR TO ELLIS-FOSTER COMPANY, A CORPORATION OF NEW JERSEY.

PROCESS OF TREATING PETROLEUM PRODUCTS.

No Drawing. Application filed December 17, 1921, Serial No. 523,208. Renewed August 22, 1924.

To all whom it may concern:

Be it known that I, CARLETON ELLIS, a citizen of the United States, and a resident of Montclair, in the county of Essex and 5 State of New Jersey, have invented certain new and useful Improvements in Processes of Treating Petroleum Products, of which the following is a specification.

This invention relates to a method of 10 treating petroleum products and relates especially to a process of cracking petroleum oils under high pressure and at a relatively high temperature or under other suitable conditions such that a mixture of aliphatic and aromatic bodies are produced and exposing the products of cracking or preferably a portion of the lighter products to the action of air or oxygen under conditions of selective oxidation whereby various oxidized products are secured which have valuable industrial uses.

An oil heavier than gasoline preferably is used for the purpose, for example kerosene or oils much heavier than kerosene, including residuum and oils of intermediate specific gravity. The oil is preferably cracked under a relatively high pressure as for example 10 to 20 atmospheres and a relatively high temperature as for example 800° or 30 900° C. The object of these drastic cracking conditions is to produce a product containing a substantial amount (that is to say preferably not less than 5%) of aromatic hydrocarbons as for example benzol, 35 toluol, naphthalene and the like. Preferably I aim to secure at least 5 to 10 per cent of aromatic hydrocarbons in the liquid products and this proportion may be desirably increased to more substantial proportions, for example 25 or 30 per cent or even 40 higher.

For example kerosene is vaporized and passed through a strongly heated tube under pressure to form gasoline and products 45 heavier than kerosene. The light products will contain some benzol and other aromatic hydrocarbons if the cracking has been carried out under sufficiently drastic conditions. Thus a product containing 10 to 15 50 per cent of aromatic hydrocarbons may be obtained which may subsequently be oxidized as will be more fully detailed below.

As drastic cracking produces a considerable quantity of fixed gases which reduce 55 the yields of liquid hydrocarbons I may

utilize these fixed gases by treatment to produce hydrogen, lamp black and other substances. Or these fixed gases may be selectively oxidized if desired to form various useful products.

Thus the fixed gases may be mixed with steam and passed over a nickel catalyzer to form hydrogen, carbon monoxide and carbon dioxide. The hydrogen is subsequently extracted and suitably purified. It 60 may then be mixed with nitrogen obtained from a subsequent stage of operation.

Or the hydrogen in the fixed gases may be separated directly therefrom by means of a diffusion device, liquefaction operations or other procedures. When the cracking has been carried out at a very high temperature a good part of the gas in some cases will be hydrogen and by putting this gas through a liquid air apparatus hydrogen 65 may be obtained in a state of comparative purity.

The liquid products obtained on condensing the vapors arising from the cracking operation are suitably distilled and various 70 fractions selected as desired to be subjected to oxidation.

In carrying out the oxidation step I preferably employ a catalyzer such as chromium oxide, vanadium oxide, iron chromate and 75 similar oxidizing catalysts. If desired these may be placed on a support or carrier such as pumice. The catalytic material is placed in a tube which is heated in a lead bath to 300° to 400° C. A temperature of 320° 80 C. is advantageous. Uniform heating and heat control is quite essential to the successful operation of the process and consequently the temperature of the lead bath should be carefully watched. Likewise it is 85 desirable to have a thermometer in the exit gases to indicate their temperature in order that the rate of flow of the gas through the catalyzing chamber may not be too rapid and thus cool the gases below a desirable 90 oxidizing temperature. The air employed may be washed to remove impurities and may then be passed through a humidifier in order that the air may be saturated with a constant amount of moisture. The air is then 95 fed into a vaporizing chamber into which the fraction of the oil which is to be treated is slowly introduced and on heating this chamber, when heat is required, vapors of the distillate are obtained admixed with air and 100 105 110

are passed onward to the catalyzing chamber. The amount of oxygen introduced should be carefully proportioned, preferably about 20 per cent being used but the proportion varying with different hydrocarbon mixtures. The amount of oxygen (or air) used is preferably less than that required for complete combustion, and for the best results the amounts used are substantially less than that required for complete combustion, that is the oxygen is about 20%. The exit gases may be treated in various ways preferably they are passed through a cooling chamber in which are cooling coils and in this chamber any solid crystalline substances, etc., will be deposited to a considerable extent. The vapors from the cooling chamber then may pass through an ordinary air-cooled or water-cooled condenser and subsequently if desired may be passed over activated carbon or silica gel. Another and preferable method of procedure is to pass the gases into the cooling chamber to collect any fatty acids and other very readily condensable substances and to pass the vapors through a scrubbing tower through which water is passed in order to collect water soluble products of oxidation and finally to pass through a scrubbing oil or into a scrubbing tower to collect the gasoline and other water insoluble liquids. It may be added however that in the water scrubbing apparatus a considerable amount of hydrocarbon may condense and this may be suitably separated. Or the products of oxidation may pass into an air-cooled condenser, then into a water-cooled condenser and finally may be scrubbed with heavy oil or may be passed over activated carbon or silica gel. By using an air condenser of large size clogging due to the separation of solid crystalline substances may be very largely avoided the apparatus being cleaned from time to time. The aqueous solution will generally be found strongly acid due to the formation of water soluble fatty acids by the oxidation. These include not only monocarboxylic acids of the acetic acid type but also dicarboxylic acids. In this manner the various products of oxidation may be collected and separated in a crude state being subsequently refined to such condition of purity as may be desired. The oxygen of the air is so completely utilized in this manner that the process affords an excellent source of nitrogen gas which may be separated from the fixed gases coming from the oxidation stage by any suitable method as for example by liquefaction methods or by absorbing the other gases in suitable absorbing agents. The nitrogen thus obtained may if desired be incorporated with hydrogen gas obtained as noted above and a purified mixture of these gases in the ratio of three volumes of

hydrogen to one volume of nitrogen may be passed under a pressure of approximately 100 atmospheres or higher into contact with an ammonia catalyst such for example as fused or sintered iron granules composed of very pure iron or other catalysts suitable for the purpose may be employed. Ammonia is formed and carried away in the exit gases to suitable absorbing agents such for example as sulphuric acid. The by-product acid obtained from refining of gasoline or other oils may be used as an absorbing agent. Ammonium sulphate is thus obtained and constitutes a useful by-product.

What I claim is:—

1. The method of treating petroleum which comprises cracking heavy petroleum oils under high pressure and at a relatively high temperature to form a mixture of aliphatic and aromatic bodies and exposing the products of cracking to contact with a heated catalyst in the presence of oxygen.

2. The method of treating petroleum which comprises cracking heavy petroleum oils under high pressure and at a relatively high temperature to form a mixture of aliphatic hydrocarbons with at least 5 per cent of aromatic bodies and exposing the products of cracking to contact with a heated catalyst in the presence of oxygen.

3. The method of treating petroleum which comprises cracking heavy petroleum oils under high pressure and at a relatively high temperature to form a mixture of aliphatic and aromatic bodies and exposing the products of cracking to contact with a heated catalyst in the presence of about 20 per cent of oxygen supplied as air.

4. The method of treating petroleum which comprises cracking heavy petroleum oils under high pressure and at a relatively high temperature to form a mixture of aliphatic and aromatic bodies and exposing the products of cracking to contact with oxygen in a heated state.

5. The method of treating petroleum which comprises cracking oils heavier than gasoline for the purpose of making motor spirit while employing a relatively high pressure and a relatively high temperature to form a mixture of aliphatic and aromatic hydrocarbons, admixing a part at least of the lighter products with air in an amount substantially less than will furnish oxygen sufficient for complete combustion and passing the mixture over a heated catalyst whereby fatty acids and other products of oxidation are obtained.

6. The method of treating petroleum which comprises cracking oils heavier than gasoline for the purpose of making motor spirit while employing a relatively high pressure and a relatively high temperature to form a mixture of aliphatic and aromatic hydrocarbons, admixing the lighter products

with air in an amount substantially less than will furnish oxygen sufficient for complete combustion and passing the mixture over a heated catalyst at 320° C. whereby fatty acids and other products of oxidation are obtained.

7. The method of treating petroleum which comprises cracking oils heavier than gasoline for the purpose of making motor spirit while employing a relatively high pressure and a relatively high temperature to form a mixture of aliphatic and aromatic hydrocarbons, admixing a part at least of the lighter products with humidified air in an amount substantially less than will furnish oxygen sufficient for complete combustion and passing the mixture over catalyst heated between 300° and 400° C. whereby fatty acids and other products of oxidation are obtained.

8. The method of treating petroleum which comprises cracking oils heavier than gasoline for the purpose of making motor spirit while employing a relatively high pressure and a relatively high temperature to form a mixture of aliphatic and aromatic hydrocarbons, admixing a part at least of the lighter products with an oxygen-containing gas in an amount substantially less than will furnish oxygen for complete combustion, passing the mixture over a heated catalyst whereby fatty acids and other products of oxidation are obtained.

9. In the process of oxidizing highly

cracked petroleum the step which comprises exposing a mixture of aliphatic and aromatic hydrocarbons, the latter present in substantial amount, to the action of an oxidizing catalyst in the presence of air whereby fatty acids and other products of oxidation are obtained.

10. In the process of oxidizing highly cracked petroleum the step which comprises exposing a mixture of aliphatic and aromatic hydrocarbons, the latter present in substantial amount, to the action of an oxidizing catalyst in the presence of humidified air whereby fatty acids and other products of oxidation are obtained.

11. In the process of oxidizing highly cracked petroleum the step which comprises exposing a mixture of aliphatic and aromatic hydrocarbons, the latter present in an amount greater than 5 per cent, to the action of an oxidizing catalyst in the presence of air whereby fatty acids and other products of oxidation are obtained.

12. In the process of oxidizing highly cracked petroleum the step which comprises exposing a mixture of volatile aliphatic and aromatic hydrocarbons, the latter present in substantial amount, to the action of an oxidizing catalyst at above 300° C. in the presence of about 20 per cent of oxygen whereby fatty acids and other products of oxidation are obtained.

CARLETON ELLIS.
